CLIP CLINCHING TOOL

Original Filed Feb. 7, 1949

2 Sheets-Sheet 2

Fig. 3

三

A detailed technical line drawing of a mechanical assembly. The drawing shows a central vertical structure with various parts labeled with numbers. On the left, a vertical cylinder is labeled '5'. Above it, a curved component is labeled '82', '92', '96', '94', '65', and '8'. To the right, a vertical pipe is labeled '14', '15', '26', and '13'. Other labeled parts include '39', '40', '12', '10', '37', '98', '37', '99', '95', '63', '25', '21', '17', and '18'. The drawing uses hatching and cross-hatching to distinguish different parts and surfaces.

CLIP CLINCHING TOOL

William D. Chilton, Royal Oak, Mich., assignor to General Motors Corporation, Detroit, Mich., a corporation of Delaware

Original application February 7, 1949, Serial No. 74,956, now Patent No. 2,647,814, dated August 4, 1953. Divided and this application November 5, 1952, Serial No. 318,917

3 Claims. (Cl. 193—38)

This invention relates to apparatus for applying a band or clip about the girth of a wire or other elongated work piece, or bundle of such work pieces, and is particularly adapted for binding together adjacent wires—for example adjacent sections of wire seat springs. The present application is a division of my application Serial No. 74,956 entitled Clip Clinching Tool, filed February 7, 1949, now Patent No. 2,647,814.

The primary object of the invention is to provide a relatively light weight, power operated, hand portable tool in which the steps of feeding a pre-formed U-shaped clip, grasping the wires or other elements to be bound and clinching the clip thereabout are carried out automatically in a single continuous, rapid operation requiring the use of only one hand of the operator.

Another object of the invention is to provide a power operated clip clinching tool wherein, during each clip clinching operation, part of the power is employed to provide a continuously directed force to move the clip into the clinching die and the remainder of the power is employed to effect an intermittent or hammering force on the clip, the magnitude of the latter force increasing progressively as the movement of the clip decreases in reaching its final clinched position.

Still another object of the invention is to provide a clip clinching tool having a clip magazine attached thereto and adapted to serve as a tool supporting hanger, the magazine being so constructed as to permit substantially unrestrained maneuvering of the tool during use without interfering with the feed of clips thereto.

Still another object of the invention is to provide a tool for clinching pre-formed U-shaped clips of the type having alternately toothed arms, including a clip receiving throat, means for yieldably retaining a clip therein ready for use, and means insuring proper alignment of the clip during its passage from the throat to a clinching anvil.

Other objects relate to the structural organization and arrangement of parts hereinafter described and claimed.

In the accompanying drawings:

Figure 1 is a top plan view of the tool embodying my invention, with portions broken away and in section, and showing the parts in clip clinching position.

Figure 2 is an enlarged sectional view of the cylinder end of the tool taken substantially on line 2—2 of Figure 1, except that the air control valve and associated elements at that end of the tool are shown rotated 56° from their true position.

Figure 3 is an enlarged view of the jaw end of the tool similar to that of Figure 1 except with the parts in position to begin a clip clinching operation.

Figure 4 is an enlarged sectional view taken substantially on line 4—4 of Figure 5.

Figure 5 is a fragmentary side view of the jaw end of the tool, with portions broken away and in section and showing the parts in clip clinching relation as in Figure 1.

Figure 6 is a detail sectional view of the feed magazine taken substantially on line 6—6 of Figure 5.

2

Figure 7 is an enlarged perspective view of an unclinched U-shaped sheet metal clip of well-known form and representative of the type which the tool of my invention is designed to clinch around one or a bundle of wires or the like.

The embodiment of the tool shown in the drawings comprises a frame 1 including a cylinder 2 closed at one end 3 and connected at its opposite end to a bifurcated or yoke-shaped head 4. The base 5 of the yoke-shaped head has an aperture 6 in line with the bore 7 of the cylinder 2 and supports spaced arms or plates 8 and 9 terminating in nose portions 10 and 11 having pockets or notches 12 and 13, respectively, for receiving work of elongated section such as wires 14 and 15.

Pivottally swingable between the plates 8 and 9 about pivots such as bolts 16 and 17 are a pair of oppositely disposed jaws in the form of rockers 18 and 19 which extend generally longitudinally with respect to the cylinder 2. The hook-shaped outer ends 20 and 21 of the rockers overlap when brought together, their inwardly curved faces 22 and 23 cooperating with each other in that position to form a female die or anvil, such that when a pre-formed U-shaped clip 24 (Figure 7) is forced legs 25 and 26 foremost thereinto its legs 25 and 26 are bent around the wires 14, 15 in the manner illustrated at 25' and 26' in Figure 5. The inner ends of the rockers 18 and 19 carry rollers 27 and 28 and are biased toward each other by springs 29 and 30 which are tensioned between pins 31, 32 and 33, 34 secured to the rockers and the plate 9, respectively. Slots 35 and 36 are provided in the plate 9 to allow clearance for movement of the pins 33 and 34 accompanying swinging of the rockers.

Extending between the plates 8 and 9 are spaced wall members 37 and 38 for supporting the clip 24 to be clinched. An opening 39 is provided in the plate 8, through which clips to be clinched may singly pass into the space between the wall members 37 and 38 during operation of the tool. The wall members 37 and 38 define the lateral extremities of a clip loading station, the forward end of which is normally closed by a pair of gates or doors 40 and 41 pivotally carried by pins 42 and 43. To retain the doors 40 and 41 in their closed positions as shown in Figure 3, spiral springs 44 and 45 are provided which engage slotted ends of the pins 42 and 43 and are anchored to the plate 9 as by pins 46 and 47. The doors 40 and 41 define the forward extremities of the clip loading station and serve to properly position the clip 24 therein preliminary to forcing the same toward the outer ends 20 and 21 of the rockers. A small permanent magnet 49 projects through the plate 9 between the wall members 37 and 38 and serves to temporarily retain the clip 24 and insure its being fully seated against the plate 9 in the loading station prior to beginning its passage forwardly to the anvil.

The spiral spring 44 and 45 allow the doors 40 and 41 to open by swinging forwardly when force is applied to the clip 24 to move it toward the anvil, and in their open position these doors form a continuation of the wall members 37 and 38 for guiding the clip in its passage. The oppositely disposed faces 50 and 51 rearwardly adjacent the inwardly curved anvil forming faces 22 and 23 on the rockers 18 and 19 cooperate with each other in the anvil forming position to guide the clip 24 during its passage after it leaves the doors 40 and 41.

The means for forcing the clip 24 against the anvil consists of a projectable pusher member 62 terminating in a clip engaging nose portion 63 at its forward end. The member 62 is slidably guided by the plates 8 and 9 in one plane and by the wall members 37 and 38 in the plane at right angles thereto. Rearwardly of its nose portion 63, member 62 is provided with cam surfaces 64 and 65 projecting from its opposite sides for engaging and

spreading apart the rollers 27 and 28 during forward movement of the member 62, whereby the hook-shaped outer ends 20 and 21 of the rockers are forced together to form an anvil and receive the clip as it is forced thereto. Connected to the rear end of the pusher member 62 is a piston indicated generally by the numeral 66, responsive to fluid pressure rearwardly thereof in the cylinder 2. The piston 66 constitutes a fluid pressure operated percussive hammer, the elements and function of which per se constitute no part of the instant invention. Included in this hammer device is a cylinder 67 within which is reciprocated a plunger 68 which strikes the rear end of the clip pusher member 62. The automatic valve mechanism 69, through which the pressure fluid is alternately admitted to opposite ends of the hammer cylinder 67 to effect the reciprocation of the plunger 68, is secured to the rear end of cylinder 67 by a longitudinally apertured cap 70 which pilots the hammer device in the bore 7 of the enclosing cylinder 2. A flexible packing 51 carried by the cap 70 provides a pressure seal between the cap and the cylinder bore 7. 72 indicates means such as a coil spring for biasing the percussive hammer (piston 66) toward the rear end 3 of the cylinder 2.

The clip pusher member 62 also constitutes the striker portion of the percussive hammer. Its rear end is formed with the usual tapered shank 80 which extends into the bore of the hammer cylinder 67 through a correspondingly tapered thrust supporting liner 81. A longitudinally split collar 82 held together by an encircling snap ring 83 is provided for loosely securing the plunger end-wise in the hammer cylinder 67. Interned flanges 84 and 85 at opposite ends of this collar engage peripheral grooves 86 and 87 on the cylinder 67 and forwardly of the tapered shank 80 on the pusher member 62. The grooves 86 and 87 are slightly wider than the thickness of the flanges 84 and 85 to provide the pusher member 62 with sufficient longitudinal freedom of movement relative to the hammer piston 67 for maximum transmission of the plunger impacts to the clip 24 being clinched.

As stated earlier, the plates 8 and 9 of the head 4 serve to guide the pusher member 62 during its sliding movements toward and away from the anvil. Adjacent their juncture with the base 5 of the head the opposing inner faces 90 and 91 of these plates are counterbored, as shown at 92 and 93 in Figures 4 and 5, to provide clearance for the collar 82 and the forward end of the hammer cylinder 67 during their movements with the pusher member 62. At the forward end of this counterbore are semi-circular abutments 94 and 95 on the plates 8 and 9 (formed as by drilling aligned holes 96 and 97 through the plates at that point). In the event the tool is operated without being loaded with a clip to be clinched, pins 98 and 99 which are carried by the pusher member 62 engage these abutments, thereby limiting the forward travel of the pusher member and preventing its nose portion 63 from striking the anvil forming faces 22 and 23 of the rockers.

The rear end 3 of the cylinder 2 is provided with inlet and exhaust passageways 112 and 113 respectively which are in alternate communication with the interior of the bore 7 of cylinder 2 through a conventional slide valve 114 and a common inlet and exhaust passage 115. Fluid, for example, air supplied under pressure through a hose 116 connected to the inlet passage 112, urges the valve 114 upwardly from its position as shown in Figure 2 to a position blocking communication between the inlet passage 112 and passage 115 and opening communication between exhaust passage 113 and passage 115, all in a manner which will be readily understood.

The valve 114 bears at its upper end against the rear arm 127 of a bell crank 128. This bell crank is journaled in a cored passage extending longitudinally through the wall of cylinder 2 and is provided at its forward end

with the finger operated control lever 129, by depressing which the operator may force the valve 114 downwardly to operate the tool. A dog 130 is secured to the bell crank 128 in proper angular relation with the arm 127 so as to strike the outer surface of the cylinder 2 when the valve 114 is in its uppermost or "exhaust" position.

Secured to the plate 8 of the yoke-shaped head 4, as by the bolts 16 and 17 about which the rockers 18 and 19 are pivoted, is a feed magazine 141. This magazine 10 comprises a flexible monorail or band 142 made of spring steel or equivalent material. Adjacent one edge 143 of the band are secured a succession of L-section brackets 144, interspaced from each other as indicated at 145. One leg 146 of each bracket 144 is spaced from one side 15 147 of the band, and the adjoining other leg 148 extends transversely thereto in spaced relation from the edge 149 of the band. A similarly shaped but heavier constructed bracket 150 connects one end of the band to the plate 8 by the bolts 16 and 17 as aforesaid. U-shaped clips 20 24 straddle the edge 149 of the band with one of their legs, either 25 or 26, disposed between the band and the bracket leg 146, as indicated in dotted lines in Figure 6. During operation of the tool, clips are stacked in this manner in end-to-end relation along the band and 25 fed by gravity through the opening 39 to the loading station defined by the wall members 37 and 38 between the plates 8 and 9 of the tool head 4. The upper end (not shown) of the band 142 may be suspended from a fixed support and the magazine 141 be used to 30 support the weight of the tool during operation. Further, the upper end of the band may be continuously fed with clips from a hopper. The interspacing of the brackets 144 preserves the flexibility of the band 142, thereby allowing the tool to be maneuvered as necessary relative to the work during operation.

The operation of the tool to clinch a clip 24 about wires 14 and 15 or other work will now be described. With finger pressure released from the lever 129 the valve 114 automatically rises due to air pressure in the 40 line 116 to open the rear end of the cylinder 2 to atmosphere through the exhaust passage 113, and the retracting spring 72 thereupon withdraws the percussive hammer piston 66 and its attached pusher member 62 toward the rear end 3 of the cylinder 2 until the clip engaging nose portion 63 is disposed just rearwardly of the wall members 37 and 38. The withdrawal of the cam surfaces 64 and 65 carried by the clip pusher member 62 allows the springs 29 and 30 to draw the rollers 27 and 28 toward each other and separate the anvil forming hook-shaped ends 20 and 21 of the rockers 18 and 19. The wires 14 and 15 may then be engaged in the notches 12 and 13 of the plates 8 and 9 ready for a clinching operation.

A clip 24 will then drop by gravity from the feed magazine 141 into the space between the wall members 37 and 38 and be retained fully seated therein by the magnet 49. The doors 40 and 41, being urged by their springs 44 and 45, will be in their normally closed positions (as 55 shown in Figure 3) and retain the clip 24 uprightly in 60 loosely abutting relation with pusher member nose portion 63.

The operator then by depressing the finger lever 129 moves the valve 114 downwardly to close off the exhaust passage 113 and open the cylinder to air under pressure 65 from the line 116 through the inlet passage 112 and the common passage 115. As pressure builds up in the cylinder bore 7 behind the percussive hammer piston 66, the latter is driven forward against its retracting spring 72, moving the clip pusher member 62 forwardly to force the clip 24 legs foremost through the doors 40 and 41 and toward the hooked shaped rocker ends 20 and 21. With continued travel of the clip pusher member 62 in this direction, its cam surfaces 64 and 65 engage the 70 rollers 27 and 28, spreading them apart and swinging the 75

hook-shaped ends 20 and 21 of the rockers 18 and 19 into anvil forming relation about the wires 14 and 15.

In addition to the progressive forward movement of the piston 66, the pressurizing of the rear end of the cylinder 2 causes the plunger 68 to reciprocate in the percussive hammer cylinder 67 and deliver striking blows to the pusher member 62. Simultaneously with its forward movement, the clip pusher member transmits the impacts delivered to it by the plunger 68 to the clip 24. The pressure within the rear end of the cylinder 2 is relatively low at the beginning of the operation and increases gradually as the retracting spring 72 is compressed during the forward movement of the piston 66 and clip pusher member 62, hence the intensity of the blows delivered to the clip 24 increases to its maximum when the clip reaches the solid backing afforded by the anvil. A thorough set of the clip legs 25' and 26' around the wires 14 and 15 is thereby finally obtained with the employment of the full power capacity of the tool. Such a permanent set is desired to prevent any tendency of the legs of the clip to unwind due to natural resilience when the clip pusher member is withdrawn.

A tool constructed as above described has proved highly satisfactory in production assembling operations on automobile seat springs wherein the various spring elements must be securely tied together with clips at widely different points requiring considerable maneuvering of the clip feeding and clinching means. By reason of its relatively light weight and generally elongated shape, my tool may be readily maneuvered to different locations about the work and its operation controlled using only one hand of the operator. When employed in this type of work by an operator of no unusual skill, my tool enables clinching from 40 to 50 clips per minute, which is several times the rate practical with any other tool of similar purpose.

Its advantageous use in seat spring assembling is mentioned merely by way of example. Obviously the tool is suitable for a wide variety of purposes where it is desired to clinch the legs of a pre-formed U-shaped member about a work piece of elongated section.

The flexible magazine assures a continuous supply of clips during operation while still permitting extensive maneuvering of the tool relative to the work.

I claim:

1. A flexible chute for delivering U-shaped articles in aligned relation between two relatively movable points, comprising a flexible band connecting said points, a plurality of article guiding members in interspaced relation along said band and separately secured thereto, said members being otherwise disconnected from each other and having adjoining portions spaced from one edge and one side of the band, respectively.

2. A flexible chute for conducting U-shaped clips from a stationary support to a movable clinching tool, comprising a flexible band for interconnecting the support and the tool, a series of clip guiding brackets spaced longitudinally from each other along the length of said band and individually secured thereto, said brackets being otherwise disconnected from each other and generally L-shaped in section with one leg of the L disposed opposite and spaced from one side face of the band and the other leg of the L disposed opposite and spaced from one edge of the band.

3. A flexible chute for conducting articles having generally U-shaped sections from one point to a second relatively movable point, comprising a flexible band connecting said points, a plurality of article guiding members in interspaced relation along said band and individually secured thereto, said members having relative freedom of movement between each other during flexure of the band and each including adjoining portions spaced from one edge and one side of the band, respectively, to accommodate passage of the adjacent legs of the article U-shaped sections between said member portions and the band.
